CLAIM

The ornamental design for a broadcasting system portable receiving terminal housing, as shown.

DESCRIPTION

FIG. 1 is a perspective view of a broadcasting system portable receiving terminal housing, embodying our new invention;

FIG. 2 is a plan view thereof;

FIG. 3 is an end view thereof; and

FIG. 4 is a side view thereof.

The broken lines shown in the drawings are for illustrative purposes only.

FIG. 1

FIG. 2

FIG. 3

FIG. 4
